(21) Appl. No.: **29/645,934**

CLAIM

(22) Filed: **Apr. 30, 2018**

We claim the ornamental design for a powerhead for wet/dry vacuum cleaner, as shown and described.

(51) LOC (12) Cl. **15-05**

DESCRIPTION

(52) U.S. Cl.

FIG. 1 is a front perspective view of a first embodiment of a powerhead for wet/dry vacuum cleaner showing the new design.

USPC **D32/21**

FIG. 2 is a front view thereof.

(58) **Field of Classification Search**

FIG. 3 is a rear view thereof.

USPC D32/21-23, 31, 34

FIG. 4 is a right side view thereof.

CPC . A47L 5/362; A47L 5/365; A47L 5/28; A47L

5/32; A47L 5/36; A47L 7/0004; A47L

7/0038; A47L 11/29; A47L 11/30

FIG. 5 is a left side view thereof.

See application file for complete search history.

FIG. 6 is a top view thereof.

(56) **References Cited**

FIG. 7 is a bottom view thereof.

U.S. PATENT DOCUMENTS

FIG. 8 is a front perspective view of a second embodiment of a powerhead for wet/dry vacuum cleaner showing the new design.

D492,824 S 7/2004 Tomasiak et al.
D507,386 S * 7/2005 Griffin D32/21

FIG. 9 is a front view thereof.

FIG. 10 is a rear view thereof.

FIG. 11 is a right side view thereof.

FIG. 12 is a left side view thereof.

FIG. 13 is a top view thereof; and,

FIG. 14 is a bottom view thereof.

The broken lines throughout the disclosure and the area visible through the openings in FIGS. 3, 4, 10 and 11 form no part of the claimed design.
